UNITED STATES PATENT OFFICE.

JOSEPH O'NEIL, OF TAYLORSTOWN, PENNSYLVANIA.

AUTOMATIC CHECK FOR OIL-WELLS.

SPECIFICATION forming part of Letters Patent No. 429,317, dated June 3, 1890.

Application filed July 24, 1889. Serial No. 318,509. (No model.)

To all whom it may concern:

Be it known that I, JOSEPH O'NEIL, a citizen of the United States, residing at Taylors-
town, in the county of Washington and State
5 of Pennsylvania, have invented certain new
and useful Improvements in Automatic
Checks for Oil-WellS; and I do hereby declare
the following to be a full, clear, and exact de-
scription of the invention, such as will enable
10 others skilled in the art to which it appertains
to make and use the same.

This invention relates to oil-well checks;
and it consists in an improved construction of
automatic oil-well checks, as hereinafter set
15 forth and claimed.

In the accompanying drawings, Figure 1 is
a vertical section of my improved check in
position in the tubing of a well. Fig. 2 repre-
20 sents a side view of the check. Fig. 3 repre-
sents a vertical section of a well-tube pro-
vided with my improved check and other de-
vices.

A designates the tubular body of the check,
the said body extending into the working-bar-
25 rel B and resting at a thereon. A ring b is
screwed to the lower end of the body A and
secures a cup-leather, which forms a close
joint with the barrel.

C indicates a housing or cage, in which is
30 placed the valve D, the said cage being
screwed to the body A and having apertures
c, which are opened and closed by the move-
ment of said valve. The valve D has a tubu-
lar stem, which extends upward, and to the
35 valve-stem is secured a stuffing-box E, which
is provided with packing d, as shown. A fol-
lower g is placed in the stuffing-box over the
packing, and a perforated cap F is screwed
to the top. The apertures e in the cap admit
40 the fluid, which presses the follower down-
ward, and thus compresses the packing. The
sucker-rod extends down through the check,
passing through the stuffing-box and check-
valve, the check being placed on the rod and
45 passed down into the tubing G.

m indicates the working-valve in the pis-
ton-head, carried by the rod h, and k indi-
cates the foot-valve in the working-barrel.
By this construction the check is automatic
in operation. At each upward stroke of the 50
rod h, which passes down through the check,
the valve D and stuffing-box are raised by the
rising fluid, which passes out through the
apertures c, and is prevented from returning
by the closing of the valve on the downward 55
stroke of the rod. The working-valve in the
piston is thus to a certain extent relieved on
the downward stroke of pressure from the oil
which has passed up through the valve-case.

The cup-leather, secured by the ring b, 60
serves to keep the body A in place and forms
a packing between the working-barrel and
the tubular body A, which prevents the pas-
sage of oil outside of said body. The pack-
ing d in the stuffing-box is compressed and 65
kept in good condition by the fluid entering
the stuffing-box through the apertures e in the
cap F and pressing down the follower g, which
is loose on the rod h.

I claim—

1. In an oil-well check, the combination,
with a tubular body, of a perforated housing
or cage secured thereto, a tubular valve placed
in said cage, a stuffing-box connected with
said valve and provided with a perforated cap, 75
a follower g, and a sucker-rod, substantially
as and for the purposes described.

2. The combination, with the tubular body
provided with a ring b and packing, of the
working-barrel B, a perforated housing se- 80
cured to said body, and a valve placed loosely
in said housing, substantially as and for the
purposes described.

In testimony whereof I have affixed my sig-
nature in presence of two witnesses.

JOSEPH O'NEIL.
